UNITED STATES PATENT OFFICE.

FRANCIS M. REINHART, OF RUDOLPH, WISCONSIN.

SILO LADDER.

Application filed August 2, 1922. Serial No. 579,153.

To all whom it may concern:

Be it known that I, FRANCIS M. REINHART, a citizen of the United States, residing at Rudolph, in the county of Wood and State of Wisconsin, have invented a new and useful Silo Ladder, of which the following is a specification.

This invention relates to silo ladders constructed for use in connection with silos which employ hoops or bands to maintain the contour of the silo.

The object of the invention is to provide a ladder made in separate units so constructed as to be detachably and easily mounted on and removed from the silo hoops.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of a portion of a silo with this improved invention shown applied, and

Fig. 2 is a detail perspective view of one of the ladder units detached.

In the embodiment illustrated, a silo 1 of any ordinary stave construction is shown having hoops 2 which encircle the staves 3 and are held by adjusting devices 4 which may be in the form of turn buckles or the like.

Attached to the hoops 2 or to as many of them as may be desired are ladder sections or units 10 each of which comprises a pair of substantially triangular shaped members 11 and 12 each constructed of heavy strap iron with the end 13 thereof lapping one of the side members 14 and secured thereto by riveting as shown at 15. These members 11

and 12 are provided at their upper ends at one corner with outwardly and downwardly turned hooks 16 which are designed to engage the hoops 2 of the silo to retain the ladder section in operative engagement. 50 The side bars 14 are provided at their other ends with sockets 17 to receive the flattened ends 19 of a cross rod 20, said ends fitting snugly within the sockets and being secured by riveting as shown at 21. The bases of the 55 triangular members are positioned at right angles to the upright bars 14 and form treads 18 to support a person using the ladder.

When the members 11 and 12 are connected by the cross rod 20, they will be held rigidly in spaced relation and the engagement of the hooks 16 with the hoops 2 of the silo will cause the bars 14 to rest against the silo and hold the ladder section 65 securely in position.

With a ladder of this construction, the independent sections or units 10 may be easily applied to the hoops 2 or removed therefrom and are strong, simple and inexpensive enabling access to the various hoops to be obtained or to the silo as to be desired.

I claim:—

A ladder section of the class described 75 comprising two substantially triangular supporting members each formed of heavy strap metal with an outturned support engaging hook at one corner, and the adjacent members at another corner arranged 80 parallel and spaced laterally to form sockets with a cross rod having flattened ends fitting and rigidly secured in said sockets.

In testimony that I claim the foregoing as my own, I have hereto affixed my signature in the presence of two witnesses.

FRANCIS M. REINHART.

Witnesses:

LOUIS JOOSTEN,
